UNITED STATES PATENT OFFICE.

CLARENCE W. TARRET, OF CHICAGO, ILLINOIS.

METAL-MOLD.

1,264,453.

Specification of Letters Patent. Patented Apr. 30, 1918.

Application filed February 9, 1917. Serial No. 147,589.

To all whom it may concern:

Be it known that I, CLARENCE W. TARRET, a citizen of the United States, residing at Chicago, in the county of Cook and State of Illinois, have invented certain new and useful Improvements in Metal-Molds, of which the following is a description; reference being had to the accompanying drawings, forming a part of this specification, in which 5 corresponding numerals of reference in the different figures indicate like parts.

The object of my invention is to provide a simple, cheap and effective metal mold which shall be so constructed as to insure the positive discharge of a metal casting therefrom as a result of opening the mold. To this end, 10 my invention consists in the combination of elements hereinafter more particularly described and definitely pointed out in the 20 claims.

In the drawings,

Fig. 1, is a front elevation of a model embodying the features of my invention,

Fig. 2, is a vertical section taken upon the line 2—, Fig. 1, viewed in the direction of the arrow there shown,

Fig. 3, is a section in plan taken upon the line 3—, Fig. 2, and

Fig. 4, is a vertical section taken upon the line 4—, Fig. 3, viewed as indicated by the arrow there shown.

Referring to the drawings 1 indicates what may be termed the primary or stationary member of a metal mold, corresponding 35 to what is ordinarily termed the "drag," and 2 the "cope" or movable member. A matrix 3, Figs. 2, 3 and 4, is formed in the part 1 while its counterpart 4 is provided in the part 2. In the example illustrated, the 40 matrix is adapted for the purpose of casting an ordinary sash-weight.

Tapped into the part 1, as shown at 5, Fig. 3, or otherwise rigidly attached thereto, are studs or clamping arms 6, 6, which are arranged parallel to each other and extended at right angles from the inner face of said member. Said studs are loosely passed through bores in the member 2 and are of a length to enable them to extend considerably beyond the outer face of said member when the mold is closed, as shown, the projecting portions being provided with racks 7 upon their under faces. A rock-shaft 8, is arranged horizontally beneath the studs 6 and 50 journaled in bearings formed in brackets 9, cast upon or rigidly attached to the outer

face of the part 2. Keyed to said rock-shaft are pinions 10, the teeth of which are adapted to engage the racks 7. An operating lever or handle 11, is rigidly attached to said rock-shaft and preferably so adjusted that when in a depending position, as shown, the mold will be closed; a reversal of its position serving to separate the parts of the mold with a positive action. 65

The following described means is provided for positively ejecting the casting from the mold should it tend to stick to the face thereof, which is liable to occur with metal molds, especially if allowed to become overheated. 70 Extending through both parts of the mold at right angles to the plane of the meeting line, viz., line 4—, Fig. 3, is an opening or passage, preferably in the form of a bore 12, a portion of which, intercepts the bore or cavity forming the matrix of the mold, in which is shown a casting 13.

Enlarged portions or bores 14 and 15 are extended inwardly from the outer faces of the mold members respectively to points substantially equi-distant from the meeting line.

An ejector, consisting in the example illustrated, of a bolt-like member 16, adapted to fit loosely but accurately in the bore 12, is of shorter length than the distance between the outer faces of the molds and is provided with heads 17 and 18 adapted to loosely enter the enlarged spaces 14 and 15 respectively so as to contact with shoulders 19 and 20 at the respective inner ends of said enlarged spaces 90 when the mold members are separated. A spline 21, adapted to slide in a well known way in a groove, not shown, formed in the bore 14, serves to prevent rotation of the ejector 16. Adjustable stops consisting of 95 screw plugs 22, 23, the latter of which is shown in Fig. 1, are tapped into the outer ends of the bores 14 and 15, as shown in Fig. 3, said plugs having bores 24 therein to provide for their manipulation and adjustment 100 by means of a spanner-wrench. A portion 25 is cut away from the body of the ejector, said portion forming a part of the matrix for each counterpart of the mold. In the example shown, it is merely a curved cut, the 105 curve of which coincides with that of the wall of the matrix. The plugs 22 and 23 are so adjusted that when the mold members are in contact, said plugs will be in contact with the ends of the ejector 16, at which time the 110 curve or cut-away portion 25 should be in exact registration with the matrix, of which,

as stated, it forms a part. Metal can then be poured into the mold and a casting made therein the same as in any metal mold.

When it is desired to eject the casting, the lever 11 is moved to a reverse position from that shown in Fig. 2 thereby forcing the mold members apart.

Assuming, in the operation, the metal to have been stuck to the matrix wall of the member 2, as the members are separated, the casting 13 and ejector 16 will be caused to move with the part 2 away from the part 1 until the head 17 is in contact with the shoulder 19 when the further movement of the lever 11 will cause that part of the cut-away portion of the ejector upon the side of the member 2 to press against the casting and force it out of the mold. Should, however, the casting stick to part 1 of the mold, the ejector will remain stationary with said part 1 until the shoulder 20 of the part 2 is in contact with the head 18, when a further movement will cause the cut-away portion of the ejector to force the casting away from contact with the part 1. It is immaterial whether the casting be stuck to one or both faces of the mold the ejector will act to effectively discharge it therefrom.

I do not wish to be limited to the construction shown inasmuch as it may be varied without departing from the principle involved.

Having thus described my invention, I claim:

1. A mold for casting metal, comprising in combination, separable counterpart mold members, an ejector forming, when in a normal position a portion of the matrix of each mold member, said ejector being loosely but positively connected with each of said members to permit a limited movement of the mold members in opposite directions in relation to said ejector, whereby, when the mold members are separated, the ejector may be forcibly drawn from each to cause the ejection of a casting therefrom.

2. A mold for casting metal, comprising, in combination, separable counterpart mold members, an ejector forming, when in a normal position, a portion of the matrix of each mold-member, said ejector having portions extending in opposite directions, one portion being slidably connected with one and the other with the other of said mold-members, stops for limiting the degree of separation of said mold members, and means for holding the inner faces of said ejector in registration with those of said mold members when the latter are closed.

3. A mold for casting metal, comprising, in combination, separable counterpart mold members, means for forcibly separating the same, an ejector forming, when in a normal

position, a portion of the matrix of each member and means for positively connecting said ejector with the body of each member with sufficient lost motion in the connecting means to permit a partial separation of said members without actuating said ejector after which a further movement may cause the same to be forced away from the inner face of each mold member to cause the ejection of a casting therefrom.

4. A mold for casting metal, comprising, in combination, separable counterpart mold members, an ejector forming, when in a normal position, a portion of the matrix of each member, means for positively connecting said ejector with the body of each member with sufficient lost motion in the connection to permit a predetermined separation of said members before said ejector is actuated to discharge a casting, means in operative connection with said members for moving and maintaining said ejector in a normal position and means for forcibly separating said members.

5. A mold for casting metal, comprising, in combination, separable counterpart movable means forming when in a normal position, a portion of the matrix of each member, means for connecting said movable means with each member of the mold while providing for play in each to cause said movable means to be moved from its normal position when the parts of the mold are separated whereby, when said parts are separated, a portion of said movable means may first be moved from the matrix of one part of the mold and upon further separation the counterpart portion of said movable means may be moved away from the matrix of the other part of said mold.

6. A mold for casting metal, comprising, in combination, separable counterpart members, movable means, forming, when in a normal position, a portion of the matrix of each member, means for holding said movable means in a normal position in registration with the matrix, means for connecting said movable means with each mold member while providing for play to enable a portion of said movable means to be successively moved from the matrix of one part of the mold with a given degree of separation of said parts, and then from the other when the separation is completed.

In testimony whereof, I have signed this specification in the presence of two subscribing witnesses, this seventh day of February, 1917.

CLARENCE W. TARRET.
